CLAIM

The ornamental design for a freezer organizer bin as shown and described.

DESCRIPTION

FIG. 1 is a top perspective view of a freezer organizer bin showing our new design;

FIG. 2 is a bottom perspective view thereof;

FIG. 3 is a front view of thereof;

FIG. 4 is a rear view of thereof;

FIG. 5 is a left view of thereof;

FIG. 6 is a right view of thereof;

FIG. 7 is a top view of thereof;

FIG. 8 is a bottom view of thereof; and,

FIG. 9 is another top perspective view thereof; showing the handles in opened position.

The broken lines illustrate portions of the freezer organizer bin that form no part of the claim.

1 Claim, 9 Drawing Sheets
